PICK-COUNTER FOR LOOMS.

1,325,911.

Specification of Letters Patent. Patented Dec. 23, 1919.

Application filed September 11, 1916. Serial No. 119,412.

To all whom it may concern:

Be it known that I, ALONZO E. RHOADES, a citizen of the United States, residing at Hopedale, county of Worcester, and State of Massachusetts, have invented an Improvement in Pick-Counters for Looms, of which the following description, in connection with the accompanying drawings, is a specification, like characters on the drawings representing like parts.

The present invention relates to pick counters for looms.

It is now the common practice in some weaving mills to pay the weavers according to the amount of cloth woven. The amount of cloth woven will depend on the total number of picks made by the loom in any period of time, and if the number of picks per unit of cloth length remains unchanged, the product will be of the uniform texture or grade desired. It is desirable, therefore, to readily ascertain at any time how many picks have been made by the loom since the last observation and knowing the number of picks per unit of cloth length in that particular grade of cloth the total length of cloth produced between the two observations is at once obtainable.

An important feature of the present invention, therefore, consists of a simple and efficient device operatively connected to a running part of the loom for counting the number of picks woven during an interval of time, so that by taking the reading of the device at any time, and later again taking the reading, the difference between the two will show the number of picks made during the interval, and the last reading will show the total picks made, from which the length of cloth produced is readily known.

The above characteristic of the invention and various other novel features will be herein fully described in connection with the accompanying drawing and then be particularly defined in the claims.

In the drawing:

Figure 1 is a side view of a loom of any usual or desired character provided with the present invention.

Fig. 2 is an enlarged face view of the pick counter showing certain of the parts in dotted lines.

Fig. 3 is a central vertical cross-section of the pick counter detached from the loom.

Fig. 4 is a perspective view showing certain of the parts of the pick counter in separated relation.

Fig. 5 is a like view showing other parts of the pick counter.

The loom frame and weaving devices connected thereto may be of any desired character, and in the present instance of the invention, the frame 1 has mounted thereon the crank shaft 2, the crank 3 of which is connected to the lay 4 by the pitman or connection 5. The lay is carried by the usual swords 6 mounted to rock about a suitable support 7, the construction being such that on rotation of the crank-shaft the lay will be moved toward and from the front of the loom, as usual of this class of devices. Each time the lay moves back during the regular operation of the loom, the shuttle is picked to lay the filling in the shed, and on the following frontward movement the lay beats up the filling to the weaving point or fell of the cloth. Mounted on the loom frame below the crank-shaft is the under or cam shaft on which is mounted the gear 8 meshing with a gear 9 of one-half the number of teeth connected to the crank-shaft, the construction being such that both of said shafts operate in unison with the lay but at different rotative speeds, and if the number of revolutions of either of these shafts is counted, the number of picks woven is at once known.

The pick counter may be connected to either the crank-shaft or the cam-shaft, or indeed to any part acting in an established relation with the lay, but in the present instance, it is shown as operatively related to the cam-shaft. The pick counter may be supported by the loom frame, and as indicated by Fig. 1 it is supported on the outer side of the frame in order that its scale and action may be conveniently inspected.

The pick counter comprises the casing 11 having an edge flange 12 upon which is supported the bearings for a worm shaft connected to the cam-shaft of the loom. In the present instance of the invention the bearings 13 for the worm shaft 14, project from a cap piece 15 which may be removably secured to the casing 11 by suitable

means, such as the screws 16, the worms 17 being conveniently located between the bearings 13, Figs. 2 and 4, to restrain longitudinal movement of the worm shaft, the end 5 18 of which is appropriately connected to the cam-shaft of the loom for rotative movement therewith.

The casing 11 has an extended bearing or hub portion 19 in which is secured the pin 10 or stud 20 by means of a set screw 21, or other suitable means. Mounted on the pin 20 for rotative movement is the worm wheel 22 which in the present instance is actuated from the cam shaft of the loom through the 15 worm 17. The worm wheel 22 has projecting therefrom the gear 23. This gear may conveniently be cast integral with worm wheel 22.

Surrounding the small gear 23 is a stationary internal gear 24. In the present instance of the invention the gear 24 may be conveniently cast integral with the ring 25 and the ring 25 may have the lugs 26 by which the ring and gear 24 may be secured 25 to the casing 11 by means, such as the screws 27. The screws 27 may pass through the lugs 26 and be threaded into lugs 28 projecting from the casing 11, although, as will be obvious to those skilled in the art, the 30 internal gear 24 may be otherwise supported in fixed position.

The pin 20 has loosely mounted thereon a second internally toothed gear provided with a different number of teeth than the fixed 35 gear 24. In the present instance of the invention the loosely mounted gear is formed as a disk 29, which for convenience of identification may be termed the inner disk, through which extends the pin 20, hereinbefore 40 described and a flange 31 from which project the teeth which constitute the internal gear 32, the construction being such that when the fixed internal gear 24 and the loose internal gear 32 are in assembled relation, as indicated in Fig. 3, an annular 45 space will be provided between these gears about the gear 23 for the reception of a traveling or floating gear 33, the teeth of which are operatively engaged with the small gear 23 and the teeth of both internal 50 gears 24 and 32, as indicated in Fig. 3. As hereinbefore noted the gears 24 and 32 have a different number of teeth. In the present instance the gear 32 has one less tooth than 55 the gear 24, the construction being such that as the worm wheel and its attached small gear 23 rotate, the floating gear 33 will be caused to travel about the small gear and by reason of the difference in the number of 60 teeth in the fixed and loose gears 24 and 32 respectively, the loose gear will be moved relatively to the fixed gear a distance of one tooth when the floating gear has made one revolution about the small gear 23.

65 The casing and the several gears so far

described may be variously formed, but the construction permits the parts to be cheaply made of castings. In order that the fixed internal gear 24 and the loose internal gear 32 may be more accurately associated and 70 maintained in operative relation with the floating gear 33, the face of the loose gear flange 31 is provided with a groove 34 into which extends a rim 35 extending from the face of the fixed gear 24, see Figs. 3 and 4.

Fixed to the pin 20 or splined thereon, is a small gear 36, the face of which rests against the outer face of the inner disk 29. The inner disk 29 carries a pin or support 37 between its periphery and axis on which is mounted a loose gear 38. Loosely mounted on the pin 20 is an outer flanged disk 39 of somewhat smaller diameter than the inner disk 29 and secured to or cast integral with the outer disk 39 is a gear 40 of the same diameter as the gear 36. The teeth of the loose gear 38 carried by the disk 29 are of sufficient depth to mesh with the teeth of both the fixed and loose gears 36 and 40 respectively. The teeth in the fixed and loose gears 36 and 40 respectively differ in number, and in the present instance of the invention, the loose gear 40 has one more tooth than the fixed gear 36, the construction being such that as the inner disk 29 is rotated, as hereinbefore described, it will carry with it the loose gear 38 which will be rotated on its own axis by engagement with the fixed gear 36, and since the number of teeth in the fixed gear 36 is one less than the number in the loose gear 40, the latter will perform the outer disk 39 will be moved or rotated the distance of one tooth each time the gear 38 completes its movement about the gears 36 and 40. In order that the pin 20 may conveniently provide a bearing for the outer disk and gear 40 without causing the gear 40 to bind against the fixed gear 36, the pin 20 is provided with a shoulder or enlargement 41 on which the outer disk 39 and gear 40 are supported, the face of the shoulder 41 resting against the face of the fixed gear 36 when the parts are in assembled relation. The pin 20 has a head 42 to rest against the face of the outer disk 39 and maintain the parts in place when the pin is secured to the bearing 19 of the casing, as hereinbefore described.

The inner disk 29 and the outer disk 39 are each cup shaped, the face flange of the former in connection with the face flange of the fixed internal gear 24 providing the desired space for the travel of the floating gear 33, and the face flange of the disk 39 bearing upon the outer surface of the inner disk 29 affording between the two disks the space or housing for gears 36, 38 and 40, forming the transfer or carry mechanism.

From the construction described, it will be noted that each rotation of the cam shaft 130

of the loom, which represents two picks, will cause movement of the worm and worm wheel and, through the described connections, impart movement to the inner disk 29 and yet slower movement to the outer disk 39, face portions of each of said disks being in convenient view. The inner disk 29 and the outer disk 39, are each provided with a scale, the divisions of which represent 10 a certain number of picks made by the loom, and to facilitate reading the scale at a glance the cap 15 is provided with a pointer 43 which overhangs the inner disk, as indicated by Fig. 3. If the numbered divisions of 15 the scale on the inner disk represent the picks in groups of a thousand, then the inner disk will register the number of picks up to thirty thousand, and the outer disk will register the total number of thirty thousand 20 picks made by the loom. Knowing the number of picks in the cloth per unit of length or per inch, the total amount of cloth woven during any period is at once ascertained.

Claims:

25 1. A pick counter for looms, comprising, in combination, a casing having a shaft secured to and projecting beyond said casing, a worm wheel loose on said shaft, a worm meshing with said wheel, mounted on said 30 casing and adapted to be attached to a loom shaft rotated in predetermined relation to the lay, a ring secured to said casing formed

to present a fixed internal gear, a cup-shaped dial member formed to present a loose internal gear having fewer teeth than said fixed gear, a fixed pinion on said shaft received by 35 said cup-shaped member, a floating gear meshing with said pinion and internal gears and received by said cup-shaped member, a smaller cup shaped dial member loose on 40 said shaft, and transfer mechanism between said dials, said smaller dial member being arranged to house said transfer mechanism.

2. A pick counter for looms, comprising, in combination, a casing, outer and inner 45 cup-shaped rotative members assembled with said casing and having dials thereon, said inner cup member and casing having circumferential tongue and groove means for guiding said inner cup member, a fixed 50 shaft projecting through said inner cup member, a driving gear loose on said shaft and having a pinion fast thereon, internal gears fast on said casing and inner cup member having an unequal number of teeth, a 55 floating gear meshing with said pinion and internal gears, transfer mechanism between said outer and inner cup-shaped rotative members, said outer member arranged to house said transfer mechanism. 60

In testimony whereof, I have signed my name to this specification.

ALONZO E. RHOADES.
